UNITED STATES PATENT OFFICE.

JOHN L. BARNES, OF LEXINGTON, KENTUCKY.

HEMP-BREAKER.

1,311,742.

Specification of Letters Patent. Patented July 29, 1919.

Application filed April 2, 1919. Serial No. 286,877.

To all whom it may concern:

Be it known that I, JOHN L. BARNES, a citizen of the United States, residing at Lexington, in the county of Fayette and State of Kentucky, have invented certain new and useful Improvements in Hemp-Breakers, of which the following is a specification.

This invention relates to improvements in machines for breaking hemp and similar fibrous material and has for its primary object to provide a machine of this character in which the stalks to be broken are fed into the machine side-wise and are intermittently acted upon at various points throughout their length during their passage through the machine by series of moving breaker bars.

Another object is the provision of a machine of this character including superposed banks of breakers, each bank consisting of a series of units and an actuating mechanism capable of varying the movement of the respective units so as to intermittently act upon the stalks at various points throughout their length.

With these and other objects in view as will appear as the description proceeds the invention comprises the novel features of construction, accompanied by elements and arrangement of parts which will be more fully described in the following specification and set forth with particularity in the claims appended hereto.

Figure 1 represents a plan view of the improved machine.

Fig. 2 represents an end elevation thereof.

Fig. 3 represents an elevation of the opposite end of the machine, and

Fig. 4 represents a fragmentary perspective view of portions of the feed rollers, breaker bars, and the actuating mechanism therefor.

Referring to the drawing in detail, where in similar reference numerals designate corresponding parts throughout the several views the numeral 5 indicates generally a supporting frame which is mounted upon axles 6 supported upon wheels 7 whereby the machine may be conveyed and the frame structure consists of a series of upright corner posts connected adjacent their lower terminals by braces 8 and at their upper terminals by transverse and longitudinal beams 8 and 9 respectively.

Supporting beams 10 are secured to the

opposite sides of the frame structure and the beam at the discharge side of the machine is disposed in a plane below the beam at the opposite side whereby the breaker bars, which will be hereinafter more fully described, are supported at an inclination permitting the stalks to slide by gravity along the bars and finally off into a suitable receptacle.

A main drive shaft 11 is supported in bearings secured at the top of the frame structure and is operated by a suitable source of power by a belt or other power transmitting device applied to a pulley 12 and the main drive shaft is connected by a belt 13 with a cam shaft 14 rotatably supported adjacent the receiving side of the machine upon the inclined brace rods 8.

A series of breaker bars 15 is arranged for sliding movement upon the supporting beams 10 and the bars are arranged in groups, of approximately 6 bars to the group and the bars of each group are connected by strips 16 whereby they are rigidly connected and formed into a unit capable of reciprocation upon the supporting beams 10. The connecting strip of each group of breaker bars is provided with a bracket 17 having pivotal connection with a belt 18 engaging a cam or eccentric 19 of the shaft 14 whereby reciprocatory movement is transmitted to the group of bars during the rotary movement of the shaft 14 and the cams are arranged in various angular relations upon the shaft 14 so that the movement of the respective bar groups varies according to the arrangement of the cams upon the shaft.

The longitudinal members 9 are connected at uniformly spaced intervals between the transverse members 8 by cross bars 20 and bearings 21 are supported upon the bars whereby the latter are utilized as supplementary means for supporting the shaft 11. A second shaft 22 is supported in parallel relation to the shaft 11 and is connected therewith by a chain or other power transmitting device 23 whereby the shafts revolve in synchronism during the operation of the machine.

The shafts 11 and 22 are provided with a number of cranks 23 and 24, respectively corresponding to the number of groups of lower breaker bars 15 and the cranks are arranged directly above said groups.

A number of groups of upper breaker bars

25 are arranged above the lower groups 15 and the bars 25 of the respective groups 25 are connected by strips 26 to which are attached upright bearing members 27 having 5 looped upper terminals connected with the crank pin of the cranks 23 and 24. As shown in Fig. 4, the strips 26 are arranged adjacent the opposite ends of the bars 25 and the upper breaker bars are arranged in staggered relation to the lower bars in order that 10 the upper bars may enter between the lower bars and more effectively separate the fibers of the hemp or other material.

The several cranks 23 and 24 are arranged 15 at various angles throughout the length of the shafts but the cranks operating each respective group of bars 25 are arranged in parallel relation in order that both terminals of the bars will be elevated and depressed in synchronism.

A pair of superposed feed rollers 30 is mounted in lateral extension 31 of the frame structure 5 at relatively high terminals of the breaker bars and the lower feed roller is 25 constantly driven during the operation of the machine to feed stalks of hemp or other fibrous material between the shanks of breakers by a drive chain 32 extending between the main drive shaft 11 and the extended terminal of the shaft of the lower feed roller. The material to be operated upon is introduced sidewise between the rollers; that is with the axes of the stalks disposed parallel with the axes of the rollers.

30 In the practical operation of the machine the lower groups of breaker bars 15 are variably moved by the connections 18 with the cams 19, the movement of the shaft 11 being transmitted to the cam shaft 14 through the drive chain 13 the rotary movement of the pins of the cranks 23 and 24 is 35 transmitted to the upper groups of bars 25 through the bearings or pitman rods 27 imparting a variable vertical reciprocating movement to the upper groups which coact with the lower bars to effectively separate the fibers of the material lying between the bars.

What I claim is:

50 1. A hemp breaker including a frame

structure, superposed series of bars movably supported in the frame structure, the bars of each series being arranged side by side and in groups, means connecting the bars of each group, crank shafts supported 55 in the upper portion of the frame, means connecting the crank pins of the shaft with the groups of the upper series whereby movement is transmitted thereto, and means for actuating the bars of the lower groups. 60

2. A hemp breaker including a frame structure, superposed series of bars supported in the frame structure by means for actuating the bars of the upper series, a cam shaft journaled in the lower portion of the frame 65 structure provided with a series of cams and means connecting the cams with the bars of the lower series to actuate the latter.

3. A hemp breaker including a frame structure, superposed series of bars supported 70 in the frame structure, a crank shaft journaled in the frame structure, means connecting the crank pins of the shaft with the bars of the upper series; whereby movement is transmitted thereto during rotary movement of the shafts, a cam shaft journaled in the lower portion of the frame structure and provided with a series of cams, and means connecting the cams with the bars of the lower series whereby movement is transmitted thereto. 75

4. A hemp breaker including a frame structure, superposed series of breaker bars supported in the frame structure, the bars of each series being arranged in groups, 80 means connecting the bars of each group, a crank shaft journaled in the frame structure provided with a series of variously disposed crank pins, means connecting the several crank pins with the respective groups of bars of the upper series, a cam shaft journaled in the lower portion of the frame structure and provided with a series of variously disposed cams, and means connecting the cams with the respective groups of the lower series whereby movement is transmitted thereto. 90

In testimony whereof I affix my signature hereto:

JOHN L. BARNES.
